CLAIM

The ornamental design for a roof debris chute, as shown and described.

DESCRIPTION

FIG. 1 is a rear, top and left side perspective view of a roof debris chute;

FIG. 2 is a rear elevation view thereof;

FIG. 3 is a front elevation view thereof;

FIG. 4 is a top plan view thereof;

FIG. 5 is a bottom plan view thereof; and

FIG. 6 is a right side elevation view thereof;

FIG. 7 is a left side elevation view thereof;

FIG. 8 is a rear, top, and right perspective view of the roof debris chute; and,

FIG. 9 is a front, top and right perspective view of the roof debris chute.

The roof debris chute is shown with a symbolic break in its length. The appearance of any portion of the article between the break lines forms no part of the claimed design.

The broken lines in the figures show environment, and form no part of the claimed design.
